UNITED STATES PATENT OFFICE.

REES POWELL, OF GRANVILLE, OHIO.

DESIGN FOR A VASE FOR CUT FLOWERS.

SPECIFICATION forming part of Design No. 34,666, dated June 18, 1901.

Application filed May 20, 1901. Serial No. 61,200. Term of patent 14 years.

To all whom it may concern:

Be it known that I, REES POWELL, a citizen of the United States, residing at Granville, in the county of Licking and State of Ohio, have invented and produced a certain new and original Design for a Vase for Cut Flowers; and I do declare the following to be a full, clear, and exact description of the invention, such as will enable others skilled in the art to which it appertains to make and use the same.

The invention relates to a new and original design for a vase for cut flowers; and it consists of the design shown in the accompanying drawing, in which the invention is shown in perspective.

The leading feature of the design consists of a hollow body A, having its upper end terminating in petal-like projections B and its lower end terminating in a stem C, above which are petal-like ornamentalations D. Merging from the side of the hollow body portion is a stake E, provided with longitudinal corrugations F.

What I claim is—

The design for a vase for cut flowers, as herein shown and described.

In testimony whereof I have hereunto set my hand in presence of two subscribing witnesses.

REES POWELL.
